Bela A. Markham
Letters Patent

The Schedule referred to in these Letters Patent and (bearing) part of
the same containing a description in the words of the said Bela
Markham himself of his improvement in the Traverse Sleigh
To all to whom these presents shall come. We st know that
J. Bela Markham of Barrelington in the County of Chittenden
and State of Vermont have invented a new and useful improve-
ment in the Traverse Sleigh and that the following is a full and
exact description of the construction and operation of the said ma-
chine as invented or improved by me viz A Bale forming
an angle of forty five degrees the ends of which are bent outwards
horizontally and bolted to a plank eighteen inches wide
which passes across the sleigh under the bottom. The angle of the
bale is bolted to the outside of the middle knee of the beam run-
ning from the plank to the pivot at the angle is seven inches
the bolt passes through a strap fastened upon the outside and
extending around the front and rear side of the knee and fasten-
ed by two bolts and also passes through a brace passing on side
of the bale bolted to the end of the beam at the top and to the
knee at the bottom. By which the fore and aft ends of the am-
bances play up and down and accommodate themselves to the make
of the road. The raves are put upon the under side of the beam
and bolted through them by the side of the knee to strengthen the
sleigh. The pack is fastened to the platform of the sleigh by three
chains one on each side and one in the centre attached to three
bushes on the platform which lets the pack down as low as the
under part of the beam and prevents the sleigh from upsetting;
at collar one and one half inch wide diameter is fastened on the
upper side of the middle beam over the knee at each end on the
forward corners which play upon circular rings on the platform
to prevent binding when turning around a double whip

plate is bolted to the tongue and fastened at each end by a stay, from the roller. The hooks to which the whiffletrees are attached pass by two straps across the double whiffletrees to the back part and fastened by an bolt, and play in a circular form towards the tongue and carried the whiffletrees inward seven inches. When the tugs or ends of the whiffletrees come in contact with any obstacle. The shoes for each runner are in two pieces, the longest piece is two feet seven inches long and one and three-fourths of an inch wide and one and one-fourth of an inch thick. The shorter piece is eight inches long and of the same width and straight on the inner part, and the outer side is curved and tapered upwards to the thickness of three-fourths of an inch and is grooved on to the larger part at the rate of the runner and sides one and one half an inch in eight inches which prevents the shoe from breaking. The bolts which fasten the shoe to the runner are counter sunk in the shoe from the hinder part leaving the fore part perpendicular and the bolts of equal thickness. All the bolts have a screw at the end and fastened with an iron nut. The tale chains to the rack; strap hooks to the runner, straps, braces, bolts and nuts, are made of good strap iron and the shoes and rollers are taken made of cast iron. What I claim, as new (and of my own invention and for which I claim an exclusive right of making, constructing, using, and according to others to be used are the application of the Tale. The Raves, under the beams, the chain slack. Rolled strap hooks to the runner near the joint shoes and bolts to the ordinary traverse sligh, which carries the load low and consequently draws easier and accommodates itself to the make of the road (skinning) obstacles and is less liable to upset than the ordinary traverse sligh. Buntington April 28th 1834.
